UNITED STATES PATENT OFFICE.

CHARLES S. SHARP, OF AUBURN, NEW YORK, ASSIGNOR TO INTERNATIONAL HARVESTER COMPANY OF NEW JERSEY, A CORPORATION OF NEW JERSEY.

DISK HARROW.

1,213,281.

Specification of Letters Patent. Patented Jan. 23, 1917.

Application filed June 10, 1912. Serial No. 702,645.

To all whom it may concern:

Be it known that I, CHARLES S. SHARP, a citizen of the United States, residing at Auburn, in the county of Cayuga and State of New York, have invented certain new and useful Improvements in Disk Harrows, of which the following is a specification.

My invention relates to disk harrows, and in particular to that type wherein two complete harrows, having two disk gangs each, are operated in tandem relation, and consists in providing improved draft connections and means whereby the angle of the gangs relative to the line of draft of the machine may be simultaneously regulated; the object of my invention being to provide an implement of the character described that will be extremely flexible in operation, the mechanism permitting short turning movements at the end of the field and a proper trailing effect and at all times under complete control of the operator. I attain these objects by means of the mechanism illustrated by the accompanying drawings, in which—

Figure 1 is a top plan view of two disk harrows arranged in tandem relation and having my invention forming a part thereof; Fig. 2 is a detached detail designed to illustrate the operation and construction of part of the draft mechanism of the front harrow and the manner of changing the angle of the gangs relative to the line of draft; Fig. 3 is a sectional end elevation of Fig. 2; Fig. 4 is a detached detail of Fig. 2 illustrating the operation of one of the swinging draft links connecting the draft frame with the disk gang frames; Fig. 5 is a side elevation, partly in section, of Fig. 1, showing also the rear portion of a tractor to which the tandem harrow is flexibly connected and from which the gangs thereof may be adjusted; Fig. 6 is a detached sectional side elevation of Fig. 1 and designed to illustrate the operation of the mechanism for regulating the operative angle of the disk gangs relative to the line of draft; Fig. 7 is a rear elevation of the forward harrow as shown in Fig. 1; Fig. 8 is a rear elevation of the rear harrow as shown in Fig. 1; Fig. 9 is a front elevation, partly in section, of one end of Fig. 8 and designed to illustrate the construction of the end bearing for the gang axles; Fig. 10 is an end elevation of Fig. 9; Fig. 11 is a detail showing the con-

struction of the vertical pivotal connection between the gang frame and the draft frame members of the rear harrow; and Fig. 12 is a vertical cross section of Fig. 11.

The same reference characters designate like parts throughout the several views.

The draft frame of the front harrow includes a substantially U-shaped member 1, having the rear ends 2 thereof arranged parallel with the line of draft and secured to a transverse draft frame member 3, and the head portion 4 thereof secured to longitudinally arranged frame members 5 spaced apart in parallel relation and having the rear ends thereof secured to the transverse frame member 3, and extending in rear thereof are curved laterally in opposite directions and have the ends thereof connected by means of a yoke member 6.

7 represents a yoke secured to the front ends of members 5 and having a vertically arranged bearing sleeve 8, in which is journaled the vertical stem 9 of a forecarriage 10, including an axle 11 connected with the lower end of the stem and having wheels 12 journaled upon opposite ends thereof, a vertically arranged draft member 13 carried by a bracket member 14 secured to the stem 9 and having the lower end thereof connected with a bracket member 15 carried by the axle.

The gang frames include transversely arranged main members 16, preferably of channel form, and having the upper ends of depending bars 17 secured thereto, the lower ends of the bars being secured to bearing boxes 18, in which are journaled the gang axles 19 carrying the disks 20, spaced apart by means of spools 21 in a well-known way, the two gangs being operative as a bumper or out-throw harrow. There are three bearing boxes for the axles of each gang, one at the inner ends and two spaced apart near the opposite ends of the axle, the two outside bearings being connected to the rear ends of the side members 22 of U-shaped draft members 23, the front portions of which are formed concentric with the vertical axes of rearwardly extending links 24 that have the front ends thereof connected with bracket members 25 secured to the draft frame member 3 and the rear ends thereof turned downward and pivotally received by bearing blocks 26 secured to the main members 16 of the gang frames in a

manner permitting an angular adjustment of the disk gangs relative to the line of draft. The head portions of the U-shaped draft members 23 engage with flanged wheels 27 that are journaled upon depending stem portions 28 forming part of bracket members 29 that are secured to the draft frame members 2, the construction permitting an easy adjustment of the gangs, and 30 represents 10 downwardly extending bracket members that are also secured to frame members 2 and engage with the front sides of the head portion of the U-shaped draft members in a manner to retain them in proper engagement with the flanged wheels.

31 represents a block slidably received between the two members 5 of the draft frame, having depending ear members 32 that carry a transversely arranged pin 33, to which 20 are connected rearwardly extending rods 34 that are provided with upturned portions at the rear ends thereof whereby said rods are connected to the inner ends of the gang frames by means of clips 35 and a forwardly 25 extending rod 36 having the front end thereof connected with the lower end of a vertically arranged evener 37 that is pivotally connected intermediate the ends thereof with the frame members 5. 30 38 represents a shaft having the front end thereof journaled in a bracket member 39 secured to the members 5 and provided with a threaded portion in rear of the bracket whereby it is operatively connected with 35 the block 31, the shaft being held against longitudinal movement by means of a collar 40 secured thereto and engaging with the rear side of bracket 39 and a universal coupling member 41 secured to the front end of 40 the shaft and engaging with the opposite side of the bracket member, and 42 represents a forwardly and upwardly inclined shaft having a coupling member 43 at the lower end thereof whereby the shaft is operatively connected with shaft 38, the body of the shaft being journaled in a swinging bearing block 44 carried by a bracket member 45 mounted upon the upper end of the stem 9 of the forecarriage, and 46 represents 50 a hand wheel secured to the upper end of the shaft whereby said shaft may be rotated in a manner to control the angle of the disk gangs relative to the line of draft.

The rear harrow includes a draft frame 55 comprising a U-shaped member 47 having parallel rearwardly extending members 48 secured to opposite ends of a transverse member 49, and supplemental draft members 50 having the rear ends thereof secured to opposite ends of the transverse member and converging inwardly and forwardly are secured to the draft frame member 47, and extending in a plane above the draft frame of the forward harrow have the 60 front ends thereof secured to a draft head

51 that is pivotally mounted upon the stem 9 of the forecarriage.

The disk gangs of the rear harrow include main frame members 52 that are pivotally connected with opposite ends of the draft frame member 49 by means of couplings 53 that include base members 54 that are secured to the frame members 52 and provided with vertically arranged stems 55 that are journaled in bearing blocks 56 secured to the draft frame member 49 and 57 represents a king bolt securing the parts in operative relation.

58 represents depending gang free members having the upper ends thereof secured 80 to the frame member 52, and their lower ends to bearing boxes 59, like in form and similarly positioned to those of the front harrow, the gang axles 60 being journaled in the bearings and carrying disks 61. The 85 gangs being arranged to turn the soil inward, it is necessary to provide bearings 62 to resist an end thrust of the axles in an opposite direction.

The bearings include a cup-shaped block 90 secured to the lower ends of depending bars 63 that have the upper ends thereof secured to opposite sides of the outside ends of the gang frame members 52. The ends of the gang axles are journaled in the blocks, and 95 64 represents washers interposed between the ends of the axle and an adjusting screw 65 whereby the associated parts of the bearing may be properly adjusted.

66 represents U-shaped draft members 100 like in form to that of draft members 23 and connecting the rear disk gangs with the members 48 in a like manner.

67 represents longitudinally arranged bars secured to the draft frame in parallel 105 relation and arranged as guides for blocks 68 that are slidably received between each pair of bars and connected with the upper end of evener 37 carried by the draft frame of the forward harrow by means of rods 69, 110 whereby the blocks are adjusted simultaneously with the block 31 and in an opposite direction, and 70 represents bars connecting the blocks 68 with the inner ends of the gang frames.

71 represents loop members secured to the inner ends of the gang frame members 52 and having the head portions thereof adapted to engage with the upper surface of bars 67 in a manner preventing a downward movement of the inner ends of the gang frames relative to the draft frames, and 72 represents bars secured to the loop members and engaging with the lower sides of the bars 67 in a manner preventing an upward movement of the inner ends of the gang frames.

The harrows are designed for use in connection with a traction engine and the hand wheel 46 is within convenient reach of the 130

operator of the engine and may be manipulated in a manner to control the working angle of the disk gangs as desired, and the rear harrow may be easily detached from the 5 forecarriage and the front harrow operated singly.

What I claim as my invention, and desire to secure by Letters Patent, is:

1. In a tractor drawn tandem disk harrow, front and rear units flexibly connected, each unit having a plurality of pivoted gang members, and unitary means positioned to be reached from a tractor for angularly adjusting all of said gangs.
2. In a tractor drawn tandem disk harrow, front and rear frames concentrically pivoted, each frame carrying a plurality of angularly adjustable disk gangs, and means positioned to be reached from a tractor for controlling the adjustment of said gangs.
3. In a tandem disk harrow, flexibly associated front and rear frames laterally pivotally connected and each carrying a plurality of angularly adjustable disk gangs, and unitary means located on the forward end of the harrow for simultaneously adjusting the angular positions of said gangs.
4. In a tandem disk harrow, front and rear frames laterally pivotally connected 30 and each carrying a plurality of pivoted gang members, and unitary means for angularly adjusting all of said gangs.
5. In a tandem disk harrow, front and rear units comprising each a pair of pivoted 35 gang members the rear unit being capable of a lateral movement relative to the front unit and the gang members being adapted to be placed in cruciform arrangement, and a single member for adjusting the angular 40 positions of all of said gang members.
6. In a tandem disk harrow, front and rear frames flexibly connected to each other, each carrying a plurality of pivoted gang members adapted to be placed in cruciform 45 arrangement, and unitary means for adjusting the angular positions of all of said gang members.
7. In a tandem disk harrow, front and rear frames each carrying a plurality of 50 angularly adjustable disk gangs, fore and aft slidable blocks carried on each of the frames, draft links between the blocks and each of the gang members, and means for moving said blocks to adjust the gang members angularly.
8. In a tandem disk harrow, front and rear frames each carrying a plurality of pivoted gang members, fore and aft slid- 60 able blocks carried on each of the frames, draft links between the blocks and gang members, and unitary means for moving said blocks to adjust the angles of all of the gang members.
9. In a tandem disk harrow, front and 65 rear frames flexibly connected and each car-

rying a plurality of angularly adjustable disk gangs, fore and aft sliding blocks on each of the frames, draft links between the blocks and disk gangs, and unitary means for moving said blocks to adjust the gangs 70 to cruciform arrangement.

10. In a tandem disk harrow, front and rear frames each carrying a plurality of angularly adjustable gang members and pivoted at their forward ends to a common 75 pivotal member.

11. In a tandem disk harrow, front and rear frames each carrying a plurality of angularly adjustable gang members, and a forecarriage to which the front ends of both 80 of said frames are pivoted.

12. In a tillage implement, a frame, a pair of inthrow disk gangs pivoted thereto, means for moving said gangs about their pivots, and anti-tilting devices for the inner 85 ends of the gangs comprising fore and aft frame bars, and a yoke member carried by each disk gang and sliding over said frame bars.

13. In a tillage implement, a frame, a 90 pair of inthrow disk gangs pivoted thereto, fore and aft extending frame bars adjacent to the inner ends of each of the disk gangs, a sliding block on each of said frame bars having a link connection with the adjacent 95 disk gang for changing the angular position of the latter, and anti-tilting devices for each of the disk gangs comprising a vertically arranged yoke member secured to the gang and passing over the adjacent frame 100 bars.

14. In a tillage implement, a plurality of harrow frames one disposed in front of the other and flexibly connected together, harrow gangs pivoted thereto and normally 105 disposed in parallel series, a plurality of gangs being in each series, links pivotally connected to the adjacent ends of each of said gang members, a member on each frame to which certain of said links are connected, and means for simultaneously adjusting 110 both of said members longitudinally of their frames to adjust their gang members.

15. In a tillage implement, a plurality of horizontally disposed flexibly connected 115 frames, a plurality of tilling gangs movable in a horizontal plane with respect thereto, roller connections on each of said frames, and an arcuate member attached to each of said gang members and engaging the roller 120 connection on each of said frame members.

16. In a tillage implement, a plurality of horizontally disposed flexibly connected frames, a plurality of tilling gangs movable in a horizontal plane with respect thereto, 125 roller connections on each of said frames, an arcuate member attached to each of said gang members engaging a roller connection on one of said frame members, and means for actuating each of said gang members to 130

move its arcuate member with respect to said roller.

17. In a tillage implement, a plurality of horizontally disposed flexibly connected frames, a plurality of tilling gangs movable in a horizontal plane with respect thereto, draft connections on each of said frames, an arcuate member attached to each of said gang members engaging a draft connection on each of said frames, and a single means for simultaneously moving each of said arcuate members with respect to its draft connection.

18. In a tillage implement, a plurality of horizontally disposed flexibly connected frames, a plurality of tilling gangs movable in a horizontal plane with respect thereto, draft connections on each of said frames, an arcuate member attached to each of said gang members engaging a draft connection on each of said frames, and means for simultaneously moving the arcuate members of the tilling gangs on one frame toward each other as the arcuate members of the other set are moved apart.

19. In a tillage implement, a frame having spaced rearwardly extending members, tilling gangs pivoted to said frame at points adjacent the ends of said frame members and movable about in a horizontal plane, a substantially U-shaped draft link attached to each gang member on opposite sides of its pivot to said frame, and a co-operating draft member carried by each frame member at a point in front of each gang pivot.

20. In a tillage implement, a frame having spaced rearwardly extending members, gang members pivoted adjacent the ends thereof and movable in a horizontal plane, a draft connection for each of said gang members comprising an arcuate member rigidly attached thereto on opposite sides of the gang pivot, and a roller connection engaging said arcuate member and carried on one of said frame members at a point in front of the gang pivot.

21. In a tillage implement, a plurality of flexibly connected frames with their forward ends pivoted at a common point, a tilling gang pivoted on each of said frames and movable with respect to the line of draft, means including a single operating member for adjusting one of said gangs relative to the line of draft, and operative connections between said adjusting mechanism and the other gang whereby said latter gang may be adjusted upon movement of the same operating member.

22. In a tillage implement, a plurality of flexibly connected frames with their forward ends pivoted at a common point, one disposed in front of the other, a plurality of tilting gangs pivoted on each of said frames and movable with respect to the line of draft, means including a single operating

member for adjusting the gangs on one frame relative to the line of draft and operative connections between said adjusting mechanism and the gangs on the other frame whereby said last mentioned gangs may be adjusted upon movement of the same operating member.

23. In a tillage implement, a plurality of flexibly connected frames with their forward ends pivoted at a common point, one disposed in front of the other, a plurality of tilling gangs pivoted on each of said frames and movable with respect to the line of draft, means including a single operating member for adjusting the gangs on one frame relative to the line of draft, and operative connections between said adjusting mechanism and the gangs on the other frame whereby said last mentioned gangs may be adjusted in an opposite direction from the gangs on the first mentioned frame upon movement of the same operating member.

24. In a tillage implement, a plurality of pivotally connected frames, a plurality of tilling gangs pivoted thereto and movable in a horizontal plane, an evener pivoted on one of said frames, link connections intermediate one end of said evener and the gangs on one of said frames, link connections between the opposite end of said evener and the gangs on the other frame, and means for moving said evener about its pivot.

25. In a tillage implement, a plurality of pivotally connected frames, a plurality of tilling gangs pivoted to each of said frames and movable with respect thereto in a horizontal plane, an evener pivoted on one of said frames, operative connections between one end of said evener and the gangs on one frame and between the opposite end of said evener and the gangs on the other frame, and means including a single operating member for adjusting said evener and thereby adjusting said gangs.

26. In a tillage implement, a plurality of pivotally connected frames disposed one in front of the other, a plurality of tilling gangs pivoted on each of said frames and movable with respect thereto in a horizontal plane, an evener pivoted on the front frame, operative connections between the gangs on said front and rear frames and the opposite ends of said evener, an operating member for said evener protruding beyond the front end of said first frame, and operative connections between said operating member and said evener.

27. In a tillage implement, a plurality of pivotally connected frames disposed one in front of the other, a plurality of tilling gangs pivoted to each frame and adjustable with respect thereto, an evener pivoted to one of said frames and movable in a vertical plane, means including a single operating member for adjusting relative to the

- line of draft the gangs on the front frame, and operative connections between said adjusting means and one end of said evener and between the opposite end of said evener and the gangs on the rear frame for adjusting said last mentioned gangs. 70
28. An implement of the class described having, in combination, two harrows operative in tandem relation, each harrow including a draft frame having disk gangs connected therewith, the draft frame of the rear harrow extending forward in a plane above that of the front harrow, and a forecarriage having the front ends of each of the said draft frames pivotally connected therewith. 75
29. An implement of the class described having, in combination, two harrows operative in tandem relation, each harrow including a draft frame having disk gangs connected therewith, the draft frame of the rear harrow extending forward in a plane above that of the front harrow, a forecarriage including means whereby it may be connected with a source of power, and having a vertically arranged stem, the front ends of each of said draft frames being journaled upon said stem. 80
30. An implement of the class described having, in combination, two harrows operative in tandem relation, each harrow including a draft frame, disk gang frames having a vertical pivotal connection with said draft frames, U-shaped draft members having the side members thereof connected with the gang frames upon opposite sides of the vertical axes thereof and having the head portions of said members formed concentric with the vertical axes of the gang frames and connected with the draft frame in a manner permitting an angular movement of the gang frames about their vertical axes, and means for adjusting said gang frames angularly. 85
31. An implement of the class described having, in combination, two harrows operative in tandem relation, each harrow including a draft frame, disk gang frames having a vertical pivotal connection with said draft frames, U-shaped draft members having the side members thereof connected with the gang frames upon opposite sides of the vertical axes thereof, and having the head portions of said members formed concentric with the vertical axes of the gang frames, flanged wheels carried by the draft frame of the harrow and engaging with the concentric portion of said U-shaped draft members, and means for adjusting said gang frames angularly. 90
32. An implement of the class described having, in combination, two harrows operative in tandem relation, each harrow including a draft frame, disk gang frames having a vertical pivotal connection with said draft frames in a manner permitting an angular adjustment thereof relative to the line of draft. 95
33. An implement of the class described having, in combination, two harrows operative in tandem relation, each harrow including a draft frame, disk gang frames having a vertical pivotal connection with said draft frames in a manner permitting said gang frames to be adjusted angularly relative to the line of draft, means for adjusting said gang frames angularly, said means including a block slidably mounted upon one of said draft frames, a threaded shaft engaging with said block and secured against longitudinal movement, means for rotating said shaft, and operative connections between said sliding block and the inner ends of said gang frames. 100
34. An implement of the class described having, in combination, two harrows operative in tandem relation, each harrow including a draft frame, disk gang frames having a vertical pivotal connection with said draft frames in a manner permitting said gang frames to be adjusted angularly relative to the line of draft, means for adjusting said gang frames angularly, said means including bars arranged in a fore and aft direction, in parallel relation, and secured to the harrow draft frame, a block slidably mounted between said bars, a threaded shaft engaging with said block and secured against longitudinal movement, a forwardly and upwardly inclined shaft having the rear end thereof connected with the front end of said threaded shaft by means of a universal coupling, a hand wheel secured to the opposite end of said inclined shaft, and operative connections between said sliding block and the inner ends of said gang frames. 105
35. An implement of the class described having, in combination, two harrows operative in tandem relation, each harrow including a draft frame, disk gang frames having a vertical pivotal connection with said draft frames, U-shaped draft members having the side members thereof connected with the gang frames upon opposite sides of the vertical axes thereof and having the head portions of said members formed concentric with the vertical axes of the gang frames and connected with the draft frame in a manner permitting an angular movement of the gang frames about their vertical axes, and means for adjusting said gang frames angularly. 110
36. An implement of the class described having, in combination, two harrows operative in tandem relation, each harrow including a draft frame, disk gang frames having a vertical pivotal connection with said draft frames, U-shaped draft members having the side members thereof connected with the gang frames upon opposite sides of the vertical axes thereof, and having the head portions of said members formed concentric with the vertical axes of the gang frames, flanged wheels carried by the draft frame of the harrow and engaging with the concentric portion of said U-shaped draft members, and means for adjusting said gang frames angularly. 115
37. An implement of the class described having, in combination, two harrows operative in tandem relation, each harrow including a draft frame, disk gang frames having a vertical pivotal connection with said draft frames in a manner permitting an angular adjustment thereof relative to the line of draft. 120

draft, means for adjusting said gang frames angularly, said means including bars arranged in a fore and aft direction, in parallel relation, and having one pair of said bars secured to the draft frame of the front harrow, and two pairs of bars to the draft frame of the rear harrow, blocks slidably mounted between each pair of bars, a threaded shaft engaging with the block carried by the draft frame of the front harrow, means for rotating said shaft, a vertically arranged evener pivotally mounted upon the draft frame in front of said sliding block and having a link connection between the lower end thereof and said block, links connecting the inner ends of the gang frames of the front harrow with said block, link connections be-

tween the opposite end of said evener and the sliding block carried by the rear harrow, and link connections between said last named block and the inner ends of the gang frames of the rear harrow whereby said gang frames may be simultaneously adjusted angularly in opposite directions. 20

36. In a tandem disk harrow, front and rear frames each carrying a plurality of angularly adjustable gang members, a forecarriage to which said frames are connected, and control means on said forecarriage operatively connected to said gang members. 25 30
